FOREIGN PATENT DOCUMENTS

CN 303855146 S 9/2016

Primary Examiner — Maria J. Edwards*Assistant Examiner* — Dina Michelle Hoeynck(74) *Attorney, Agent, or Firm* — CANTOR COLBURN LLP(57) **CLAIM**

The ornamental design for binoculars, as shown and described.

DESCRIPTION

FIG. 1 is a front, top and left side perspective view of binoculars showing my new design;

FIG. 2 is a rear, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The evenly-spaced broken lines illustrate portions of the binoculars that form no part of the claimed design. The dash-dotted broken lines denote the boundary of the claim and form no part of the claimed design.

1 Claim, 8 Drawing Sheets(56)
